UNITED STATES PATENT OFFICE.

JOHN R. SHELDON, OF CAMBRIDGE, MASSACHUSETTS.

COMFORTER-FILLING MACHINE

1,027,570.

Specification of Letters Patent.

Patented May 28, 1912.

Application filed February 9, 1911. Serial No. 607,723.

To all whom it may concern:

Be it known that I, JOHN R. SHELDON, of Cambridge, in the county of Middlesex and State of Massachusetts, a citizen of the United States, have invented a new and useful Improvement in Comforter-Filling Machines, of which the following is a specification.

My improvement relates especially to machines for filling comforters, pillows and the like with down or feathers. In such machines as heretofore made an air blast from a blower or from a compressed air tank has been used to blow the feathers from a receptacle through a suitable nozzle into the comforter or a section of it which is temporarily attached to the nozzle. In such machines the air blast sometimes drives the down into the nozzle too rapidly so that it clogs and the blast has to be shut down until the nozzle is cleared out. Moreover when one of the sections of the comforter is filled the blast must be shut off until the next section is adjusted on the nozzle.

In a machine embodying my invention provision is made to relieve the clogging above referred to and also to prevent the delay which is due to shutting down the air blast from the flue and starting it up again.

My invention will be understood by reference to the drawings in which a machine embodying my invention in its simplest form is shown.

Figure 1 is a vertical section, and Fig. 2 is a front elevation of such a machine.

A is a covered receptacle serving as a reservoir to receive the down with which a comforter is to be filled. This receptacle or tank is filled through the pipe A¹ from any convenient source of supply and by any convenient means. The lower part of the receptacle A is provided with an apron α closing the corners of the bottom of the receptacle so that down cannot collect therein. The receptacle is also provided with an opening preferably in the side and closed by a cover A² bolted or otherwise attached thereto.

B is a shaft mounted in two opposite walls of the receptacle and having on it a number of blades B¹ by means of which when the shaft is rotated the feathers are agitated and kept within reach of the blast by which they are withdrawn from the receptacle. Power is applied to the shaft through the pulley B² and it may be rotated at any de-

sired speed. By this means the feathers are kept from packing in the receptacle.

C is a fan or blower of a type well known by means of which the feathers are conveyed from the receptacle to the comforter or other article to be filled. For this purpose there is provided an outlet D from the receptacle A which outlet leads into the fan C. The outlet from the fan comprises the pipe E which terminates in the nozzle E¹ to which the article to be filled is attached. The part D has preferably an enlarged or conical mouth D¹ through which the feathers are drawn in and the part D is preferably located at the top of the receptacle so that the feathers agitated by the blades will be drawn up into the fan rather than drawn in bulk into the feed pipe. It may, however, be located in the side if preferred. As is intimated above, the fan tends to create a vacuum in the receptacle A and the feathers passing through the fan are driven through the pipe E and nozzle E¹ into the article to be filled.

At the lower end of the pipe E near the nozzle is a return pipe F connecting the pipe E with the receptacle A and pivoted at the junction of the pipes E and F is a gate f having a handle f¹ extending out from the pipe by means of which the position of the gate may be changed. As shown in full lines in Fig. 1, the gate is in position to close the outlet through the nozzle E¹ and when in this position the feathers driven by the fan through the pipe E will pass over the gate and up the pipe F and back into the receptacle. This is the position of the gate while an article which has been filled is being removed from the nozzle and an unfilled article is being put in its place. When the unfilled article is attached to the nozzle the gate f is moved into the position shown in dotted lines in Fig. 1 so as to have a clear passage for the feathers to the nozzle. Thus the filling operation may be interrupted from time to time as occasion may require without shutting down the fan, and much time saved in the course of a day as the blast is always available when wanted, and no time is wasted in speeding up and slowing down the fan as at present is the custom. In fact this feature alone adds about one third to the present capacity of a machine of this class.

While there is but little chance that a machine operated under these conditions of

agitation and vacuum feed will become clogged, as an additional precaution against such a possibility, I prefer to provide a second fan or blower G which has an outlet pipe g terminating at g¹ just inside of the horizontal part of the pipe G and provided with a valve g² by which the blast therefrom may be controlled. When any tendency to clog is apparent the valve g² is opened and a jet of air is directed into the nozzle from the end of the pipe g which soon clears out the nozzle E'.

Other embodiments of my invention will readily occur to one skilled in the art.

The agitation of the feathers is desirable but not always essential, the main feature of my invention residing in the drawing of the down or feathers from the receptacle A rather than forcing them from the receptacle, another feature being the valve and return pipe by means of which a constant stream of feathers is passing through the fan or blower to be drawn upon to fill the comforter or other article when such filling is to take place.

I prefer to use a fan or blower of the inclosed type, but I do not mean to limit myself to such a type, nor is it necessary that the connection between said blower and receptacle be in the top wall of the receptacle as shown. Such an arrangement assures, however, the drawing of the feathers out of the receptacle by rarefied air rather than the packing of them into the outlet of a forced blast. So far as I know the drawing of the feathers from the receptacle by rarefied air is new with me. The contents of said receptacle may be agitated by other means than that shown, but a shaft as shown is perhaps as simple and at the same time as effective a device for the purpose as can be desired.

By the word "receptacle" I mean, as I have intimated above, a reservoir or tank from which a constant supply of feathers may be drawn according to the requirements of the work. In certain aspects of my invention, however, such reservoir or tank is not necessary, though convenient—and for 50 the fan may be substituted any equivalent by

which suction may be secured to withdraw feathers from a source of supply and feed them to the nozzle or end of the pipe leading to the article to be filled.

What I claim as my invention is:—

55

1. In a comforter-filling machine, a receptacle adapted to contain a supply of material, an agitator located in said receptacle and comprising a series of rotating blades, an outlet in the upper part of said receptacle, 60 a nozzle connected with said outlet, and a fan located between said outlet and said nozzle and serving to withdraw the agitated contents from said receptacle by suction and to force them outward through said nozzle. 65

2. In a machine for filling comforters, a receptacle, a fan connected to said receptacle to withdraw the contents therefrom, a nozzle connected to said fan to receive said contents from said fan and deliver them, a return pipe connecting said nozzle with said receptacle, and a gate located and adapted to close said nozzle or said return pipe as set forth. 70

3. In a machine for filling comforters, a receptacle, a nozzle, means for driving the contents of said receptacle through said nozzle, and auxiliary means comprising a fan and a pipe therefrom leading to said nozzle whereby an auxiliary blast may be 80 availed of to clear said nozzle. 75

4. A filling apparatus comprising a nozzle, means for forcing the filling material through said nozzle, and means, leading to said nozzle, whereby an auxiliary blast may 85 be availed of to clear said nozzle.

5. A filling apparatus comprising a nozzle to deliver the filling to the comforter, a source of supply of filling material, means connected to said nozzle and adapted to withdraw the filling from said source of supply and deliver it to said nozzle, a return pipe connecting said nozzle with said source of supply, and a gate located and adapted to close said nozzle or said return pipe, as 90 set forth. 95
